US00D578010S

(12) **United States Design Patent**
Friedland et al.

(10) **Patent No.:** **US D578,010 S**
(45) **Date of Patent:** **** Oct. 7, 2008**

(54) **HEXAGON SHAPED VACUUM POUCH**

(75) Inventors: **Jason Friedland**, Franklin, TN (US); **Angel Hernandez**, Nolensville, TN (US); **Rebecca Morgan Valentine**, Franklin, TN (US); **Peter Slusarczyk**, Nolensville, TN (US)

(73) Assignee: **MARS, Incorporated**, McLean, VA (US)

(**) Term: **14 Years**

(21) Appl. No.: **29/287,510**

(22) Filed: **Aug. 17, 2007**

(51) **LOC (8) Cl.** **09-05**

(52) **U.S. Cl.** **D9/707**

(58) **Field of Classification Search** D9/703-710, D9/713-714, 430-433, 414, 418, 424; 383/45, 383/47, 84, 100, 103, 107, 108, 113, 114, 383/200, 203; 229/200, 87.06; 426/106

(57) **CLAIM**

The ornamental design for a hexagon shaped vacuum pouch, as shown and described.

DESCRIPTION

FIG. 1 is a perspective view of a hexagon shaped vacuum pouch showing our new design;

FIG. 2 is a top view of the design shown in FIG. 1, wherein the bottom view is identical or a mirror image thereof;

FIG. 3 is a front view of the design shown in FIG. 1;

FIG. 4 is a rear view of the design shown in FIG. 1; and,

FIG. 5 is a right side view of the design shown in FIG. 1, wherein the left view is identical or a mirror image thereof.

The broken lines shown in the drawing are for illustrative purposes only and form no part of the claimed design.

UNITED STATES PATENT AND TRADEMARK OFFICE
CERTIFICATE OF CORRECTION

PATENT NO. : Des. 578,010 S
APPLICATION NO. : 29/287510
DATED : October 7, 2008
INVENTOR(S) : Jason Michael Friedland et al.

Page 1 of 1

It is certified that error appears in the above-identified patent and that said Letters Patent is hereby corrected as shown below:

Title Page; item (75);
Delete the second inventor's last name incorrectly shown as "HERNANADEZ" and
insert --HERNANDEZ--.

Signed and Sealed this

Thirtieth Day of December, 2008

JON W. DUDAS
Director of the United States Patent and Trademark Office
